TREATMENT OF HYDROCARBON OIL

Claude W. Watson, Dobbs Ferry, N. Y., assignor,
by mesne assignments, to Texaco Development
Corporation, New York, N. Y., a corporation of
Delaware

Application November 6, 1937, Serial No. 173,076

6 Claims. (Cl. 196—49)

This invention relates to improvements in methods of converting high boiling hydrocarbons into low boiling hydrocarbons.

According to my invention a crude oil, topped crude oil or other heavy oil is distilled to remove lower boiling constituents therefrom and to separate desirable fractions therefrom comprising preferably a heavy reflux condensate such as heavy gas oil, a light reflux condensate such as 10 light gas oil, a heavy gasoline or naphtha fraction and a light distillate containing gasoline constituents.

The crude residue resulting from this distillation is subjected to cracking to produce additional 15 quantities of intermediate constituents which may be further cracked to produce gasoline. The cracked products from the cracking treatment may be mixed with the cracked products resulting from cracking and reforming the 20 heavy naphtha fraction and the combined stream passed to a separating zone wherein vapors are separated from liquid residue. The vapors are fractionated and separated into a heavy reflux condensate, a light reflux condensate, a heavy naphtha fraction and a light distillate product.

The heavy reflux condensate last mentioned is preferably mixed with the heavy reflux condensate fraction separated from the feed stock and the combined stream is subjected to a separate 30 cracking treatment to produce additional quantities of intermediate constituents which are suitable for further conversion under drastic conditions into gasoline. The cracked products from this separate cracking treatment are introduced 35 into the separating zone above mentioned and vapors are separated from liquid residue along with the products from the cracking zone first mentioned.

The light reflux condensate separated from 40 the products from the cracking zone first mentioned is preferably mixed with the light reflux condensate fraction separated from the feed stock and the combined stream is passed through a separate cracking zone wherein the oil is maintained under high temperature and high pressure 45 conditions to effect the desired extent of cracking thereof. The cracked products are passed to a separate evaporator to separate vapors from liquid residue. The vapors are fractionated to separate condensate oil containing insufficiently cracked products from a final distillate product having the desired boiling range. The condensate oil last mentioned is recycled through the high temperature and high pressure 50 cracking zone for further cracking treatment.

along with the light condensates derived from the products from the other cracking treatments above described.

The heavy naphtha fraction separated from the feed stock together with the heavy naphtha fraction separated from the products leaving the cracking zones above described is preferably passed through a reforming and cracking zone to improve the anti-knock quality thereof and the products from the reforming and cracking zone 10 are preferably mixed with the products from the other cracking zones above described prior to their introduction into the separating zone first mentioned or they may be separately introduced 15 into this separating zone.

Having described the general nature and object of my invention, I will now give a detailed description thereof in which reference will be made to the accompanying drawing which represents a 20 diagrammatic showing of apparatus suitable for practicing my invention.

Referring now to the drawing, the reference character 10 designates a pump which forces 25 fresh charging oil such as crude oil, topped crude oil or other heavy oil through a line 12 into the bottom portion 13 of a crude stripping or fractionating tower 14 wherein the charging oil is subjected to distillation and liberated vapors are fractionated in passing upwardly in the tower 14. The stripper or fractionating tower 14 may 30 be maintained under atmospheric or superatmospheric pressure. The fresh charging oil is preferably preheated to a distilling temperature in any suitable manner as by being brought into indirect heat exchange with hot products obtained 35 during the subsequent cracking operations of the process or by being heated in a preheating coil.

The stripping or fractionating tower 14 is provided with trapout tray 16 having a hood 18, trapout tray 22 having a hood 24, and a trapout 40 tray 26 having a hood 28. The trapout trays are vertically spaced within the stripper or fractionating tower 14 so that several fractions may be collected and withdrawn from the tower 14 during distillation and fractionation of the introduced heavy oil.

During distillation and fractionation of the heavy oil in the stripper or fractionating tower 14, it is separated into fractions and a liquid residue. A heavy reflux condensate such as a heavy 50 gas oil collects on trapout tray 16. A relatively light reflux condensate such as a light gas oil collects on trapout tray 22. A naphtha fraction collects on trapout tray 26. The vapors remaining after the distillation and fractionation leave the 55

stripper or fractionating tower through line 30 and are passed through condenser 32 to form a distillate which is collected in receiver 34 having a valved gas outlet 36 and a valved liquid outlet 38. A portion of the distillate may be returned to the top portion of the stripper or fractionating tower 14 as reflux by being passed through line 40 by pump 42. If desired, a cooling coil 44 may be used at the top of the stripper or fractionating tower 14 to provide additional cooling for the top thereof.

The liquid residue collected at the bottom of the stripper or fractionating tower 14 is withdrawn and passed through line 46 by pump 48 and is passed through a viscosity breaking coil or zone 50 in furnace or heater 52 to produce a relatively large yield of intermediate constituents suitable for further conversion into gasoline constituents. The products leaving the viscosity 20 breaking zone or coil 50 are passed through line 54 preferably having a pressure reducing valve 56 into the evaporator or separating zone 58 of the combined evaporator and fractionating tower 60. If desired, a quench oil may be introduced 25 into the stream of products through line 62. In the evaporator or separating zone 58 the products are separated into a liquid residue and vapors, the liquid residue being withdrawn through line 64 and may be further treated in any suitable 30 manner. The vapors are fractionated as they pass through the fractionating section 65 of the combined evaporator or fractionating tower 60 to separate a heavy reflux condensate therefrom. The heavy reflux condensate is collected on trapout tray 66 having a hood 67 at the bottom of the fractionating section 65.

The heavy reflux condensate is withdrawn from the trapout tray 66 and is passed through line 68 by pump 70 and is mixed with heavy reflux condensate which is withdrawn from trapout tray 16 in the stripper or fractionating tower 14 and passed through line 72 by pump 74. The combined stream of heavy reflux condensates is passed through line 76 and through a second 45 viscosity breaking zone or coil 78 in furnace or heater 80. The heavy reflux condensates are preferably subjected to somewhat higher temperature and pressure conditions than the crude residue passing through the first viscosity breaking zone 50 for the reason that the amount of coke-forming constituents has been reduced 50 therein. The products leaving the second viscosity breaking zone or coil 78 are passed through line 82 preferably having a pressure reducing valve 84 and are mixed with the products coming 55 from the first mentioned viscosity breaking zone or coil 50.

The top of the combined evaporator and fractionating tower 60 may be provided with a coil 86 to provide cooling means for the top of the tower. The vapors remaining after fractionation in the tower 60 leave the top of the tower and pass through line 88 into the bottom portion of a fractionating tower 90 where fractionation of 65 the vapors occurs in fractionating section 91 to separate a light reflux condensate therefrom which collects on the bottom of the tower 90 and which is withdrawn through line 92. Near its top portion the fractionating tower 90 is provided with a trapout tray 94 having a hood 96. The vapors are further fractionated in the upper fractionating section 98 of the fractionating tower 90 to separate a naphtha fraction therefrom which is collected on trapout tray 94. This 70 naphtha fraction is withdrawn from the trapout

tray 94 and passed through line 100 by pump 102 and through the reforming and cracking zone or coil 104 in furnace 106 wherein the naphtha fraction is maintained under superatmospheric pressure and high temperature conditions in order to effect the desired cracking and reforming thereof.

The naphtha fraction withdrawn from trapout tray 94 is preferably admixed with the naphtha fraction which is withdrawn from trapout tray 26 in the stripper or fractionating tower 14 and passed through line 108 by pump 110. The combined stream is then passed through the reforming or cracking zone or coil 104 as just described. The products leaving the reforming or cracking zone or coil 104 are passed through line 114 having a pressure reducing valve 116 and are preferably admixed with the products leaving the first mentioned viscosity breaking zone or coil 50 and the second viscosity breaking zone or coil 78, the combined stream being introduced into the evaporator or separating zone 58 of the combined evaporator and fractionating tower 60 to separate vapors from liquid residue as before described. The products leaving the reforming and cracking zone 104 are at a relatively high temperature and by mixing them with the products from the cracking zones 50 and 78, further vaporization of the light constituents in the last mentioned products is obtained.

The top portion of the fractionating tower 90 may be provided with a coil 118 to provide cooling for the top of the tower 90. The vapors remaining after fractionation in the fractionating tower 90 are passed through line 120 and condenser 122 to form a distillate which is collected in receiver or drum 124 having a valved gas outlet 126 and a valved liquid outlet 128. A portion of the distillate may be passed through line 130 by pump 132 and returned to the top portion of the fractionating tower 90 as reflux.

The light reflux condensate withdrawn from the bottom of the fractionating tower 90 through line 92 is passed through line 134 by pump 136 and through a cracking zone or coil 138 in furnace or heater 140 wherein the oil is maintained under high temperature and high pressure conditions in order to effect the desired conversion of the oil. Before being passed through the cracking zone or coil 138, the light reflux condensate passing through line 134 is preferably mixed with the light reflux condensate which is withdrawn from trapout tray 22 in the stripper or fractionating tower 14 and passed through line 142 by pump 144. The combined stream is passed through the cracking zone or coil 138 as just described. The products leaving the cracking zone or coil 138 are passed through line 146 having a pressure reducing valve 148 and into an evaporator or separating zone 150. A quench oil may be introduced into the stream of products through line 152. In the evaporator or separating zone 150 the products are separated into vapors and liquid residue, the liquid residue being withdrawn from the bottom of the zone 150 through line 154.

The vapors leave the top of the evaporator or separating zone 150 through line 156 and are passed into the bottom portion of a second fractionating tower 158 wherein the vapors are fractionated and separated into a condensate oil and a final distillate having the desired boiling range. The condensate oil is withdrawn from the bottom of the fractionating tower 158 and passed through line 160 by pump 162 and preferably ad-

mixed with the light reflux condensate which is withdrawn from the bottom of the fractionating tower 90 and passed through line 134 and preferably admixed with the light reflux condensate which is withdrawn from tapout tray 22 in tower 14 and passed through line 142. The combined stream of condensate oil and light reflux condensate is passed through the cracking zone or coil 138 as before described.

10 The top portion of the fractionating tower 158 may be provided with a coil 164 to provide cooling for the top of the tower. The vapors remaining after fractionation in the fractionating tower 158 leave the top of the tower through line 166 and are passed through condensed 168 to form a distillate which is collected in receiver 170 having a valved gas outlet 172 and a valved liquid outlet 174. A portion of the distillate may be passed through line 176 by pump 178 and returned to the top portion of the fractionating tower 158 as reflux.

A typical operation contemplated by my invention will now be given but it is to be understood that I am not to be restricted thereto. The 25 fresh charging oil such as a crude oil is pre-heated to a distilling temperature of about 600-800° F. in any suitable manner and is introduced into the crude stripper or fractionating tower 14 maintained under a pressure from atmospheric 30 pressure to about 100 pounds per square inch. During distillation and fractionation the heavy charging oil is separated into fractions and a liquid residue. The liquid residue has an initial 35 boiling point of about 650-750° F. The separated fractions comprise a heavy reflux condensate such as a heavy gas oil consisting essentially of constituents boiling above 650-750° F. collected on trapout tray 16, a light reflux condensate such as a light gas oil having an end point of 40 about 650-750° F. which is collected on trapout tray 22 and a heavy naphtha fraction having an initial boiling point of about 250-350° F. and an end point of about 450-550° F. which is collected on trapout tray 26. A light distillate product is collected in receiver 34.

The liquid residue from the bottom of the crude stripper or fractionating tower 14 is passed through the once-through viscosity breaking zone or coil 50 wherein it is maintained under 50 a pressure of about 75 to 400 pounds per square inch and at a temperature of about 850-950° F. preferably with such time of reaction that the cracking is the maximum allowable consistent with the length of run due to coke formation. By operating in this way to obtain the maximum amount of conversion in the viscosity 55 breaking zone 50, a maximum overall yield of gasoline from the entire process is obtained and the total gasoline product has a higher anti-knock value. The products leave the viscosity breaking coil or zone 50 at a temperature, for example, of about 880° F. and under a pressure of about 200 pounds per square inch.

The heavy reflux condensate which is collected 60 on trapout tray 66 in the combined evaporator and fractionating tower 60 consists essentially of constituents boiling above 650-750° F. and this heavy reflux condensate is combined with the heavy reflux condensate which collects on trapout tray 16 in the crude stripper or fractionating tower 14. The combined stream is passed through the recycling viscosity breaking zone or coil 78 wherein the oil is maintained under a pressure of about 75 to 1000 pounds per square 70 inch and a temperature of about 900 to 1000° F.

to effect further conversion of heavy constituents of the oil into a relatively large amount of intermediate constituents suitable for further cracking under more drastic conditions in cracking zone or coil 138. The treated heavy reflux condensates leave the recycling viscosity breaking zone or coil 78 at a temperature, for example, of about 950° F. and under pressure of about 400 pounds per square inch.

The heavy naphtha fraction which collects on trapout tray 94 in the fractionating tower 90 has an end point of about 550 to 650° F. and contains gasoline constituents separated from vapors derived from the cracking zones 50 and 78. This heavy naphtha fraction is preferably mixed with 10 the heavy naphtha fraction withdrawn from the trapout tray 26 in the crude stripper or fractionating tower 14 and the combined stream passed through the reforming or cracking zone or coil 104. In the reforming or cracking zone 15 or coil 104 the stream of heavy naphtha fractions is subjected to a pressure of about 500 to 1000 pounds per square inch and is maintained at a temperature of about 950 to 1150° F. to effect the 20 desired conversion of the gasoline constituents thereof. The treated naphtha fraction leaves the cracking zone or coil 104 at a temperature, for example, of about 1050° F. and under pressure of about 750 pounds per square inch.

The streams of products leaving the once-through viscosity breaking zone or coil 50, the recycling viscosity breaking zone or coil 78 and the reforming or cracking zone or coil 104 are 30 preferably combined and introduced into the evaporator or separating zone 158 of the combined evaporator and fractionating tower 60 wherein a separation into vapors and liquid residue occurs. The highly heated products from the cracking and reforming zone 104 assist in 35 vaporizing light constituents from the viscosity broken products from the viscosity breaking zones 50 and 78.

The light reflux condensate collected at the bottom of the fractionating tower 90 has an end point of about 650 to 750° F. and is admixed 45 with the light reflux condensate oil collected on trapout tray 22 in the crude stripper or fractionating tower 14 and with the condensate oil withdrawn from the bottom of the fractionating tower 158. The combined stream is passed 50 through the cracking zone or coil 138 wherein the oil is maintained under a pressure of about 200 to 1000 pounds per square inch and at a temperature of about 900 to 1050° F. to effect the desired cracking of the oil. The products 55 leave the cracking zone or coil 138 at a temperature, for example, of about 990° F. and under a pressure of about 400 pounds per square inch and are separated into vapors and liquid residue. The vapors are fractionated to separate the condensate oil above described from a distillate such as gasoline having the desired boiling range. The distillate is collected in receiver 170 and 60 may be further treated as desired.

The light distillates collected in receivers 34 65 and 124 may be combined with the naphtha fractions and subjected to reforming and cracking in the reforming zone 104 or may be otherwise treated as desired.

While I have described a particular embodiment of my invention, it is to be expressly understood that my invention is not restricted thereto, and that various modifications and adaptations thereof may be made without departing from the spirit of the invention.

I claim:

1. A process for converting higher boiling hydrocarbons into lower boiling hydrocarbons which comprises subjecting crude petroleum charging stock to fractional distillation to separate a liquid residue from a heavy gas oil condensate and a light gas oil condensate, passing the liquid residue through a viscosity breaking zone wherein the residue is subjected to cracking to effect conversion into lower boiling constituents including a relatively large yield of intermediate constituents, passing the products from the viscosity breaking zone to a separating zone to separate vapors from a liquid residue, fractionating the separated vapors to separate a second heavy gas oil condensate from a second light gas oil condensate comprising intermediate constituents formed in the viscosity-breaking operations of the process, combining the first and second heavy gas oil condensates and passing them through a second viscosity breaking zone wherein the condensates are subjected to cracking to effect conversion into a relatively large yield of intermediate constituents, passing the products from said second viscosity breaking zone into said separating zone to separate vapors from a liquid residue, combining the first and second light gas oil condensates and passing them through a cracking zone wherein the condensates are maintained under high temperature and superatmospheric pressure conditions to effect the desired conversion, passing the products from said cracking zone to a second separating zone to separate vapors from a liquid residue and fractionating the last mentioned vapors to separate a distillate having the desired boiling range from condensate oil.
2. A process as defined in claim 1 wherein the condensate oil is combined with the light reflux condensates and the combined stream passed through said cracking zone to effect cracking thereof.

3. A process for converting higher boiling hydrocarbons into lower boiling hydrocarbons which comprises subjecting crude petroleum charging stock to fractional distillation to separate a liquid residue from a heavy gas oil condensate, a light gas oil condensate and a naphtha fraction, passing the liquid residue through a viscosity breaking zone wherein the liquid residue is subjected to cracking to effect conversion thereof into lower boiling constituents including a relatively large yield of intermediate constituents, passing the products from the viscosity breaking zone to a separating zone to separate vapors from a liquid residue, fractionating the separated vapors to separate a second heavy gas oil condensate and a second light gas oil condensate comprising intermediate constituents formed in the viscosity-breaking operations of the process from a second naphtha fraction, combining the first and second heavy gas oil condensates and passing them through a second viscosity breaking zone wherein the condensates are subjected to cracking to effect conversion thereof into a relatively large yield of intermediate constituents, passing the products from said second viscosity breaking zone into said separating zone to effect separation

of vapors from a liquid residue, combining the naphtha fractions and passing them through a cracking zone maintained under high temperature and high pressure conditions to effect the desired extent of cracking and reforming, passing the products from the cracking zone into said separating zone to separate vapors from liquid residue, combining the first and second light gas oil condensates and passing them through a second cracking zone wherein the condensates are maintained under high temperature and superatmospheric pressure conditions to effect the desired conversion thereof, passing the products from said second cracking zone to a second separating zone to separate vapors from a liquid residue and fractionating the last mentioned vapors to separate a distillate having the desired boiling range from condensate oil.

4. A process as defined in claim 3 wherein the condensate oil is combined with the light reflux condensates and the combined stream passed through said second cracking zone to effect cracking thereof.

5. A process for converting higher boiling hydrocarbons into lower boiling hydrocarbons which comprises subjecting crude petroleum charging stock to fractional distillation to separate a liquid residue from a heavy gas oil condensate and a light gas oil condensate, passing the liquid residue through a single-pass viscosity breaking zone wherein the liquid residue is subjected to cracking to effect conversion thereof into lower boiling hydrocarbons including a relatively high yield of intermediate constituents, passing the products from the viscosity breaking zone to a separating zone to separate vapors from a liquid residue, fractionating the vapors to separate a second heavy gas oil condensate from a second light gas oil condensate comprising intermediate constituents formed in the viscosity-breaking operations of the process, recycling the second heavy gas oil condensate together with the first heavy gas oil condensate through a second viscosity breaking zone wherein the condensates are subjected to cracking to effect conversion thereof into a relatively high yield of lower boiling constituents including a large proportion of intermediate constituents, passing the products from the recycling viscosity breaking zone into said separating zone to separate vapors from a liquid residue, combining the first and second light gas oil condensates and passing them through a cracking zone wherein the condensates are maintained under high temperature and high pressure conditions to effect the desired conversion thereof, passing the products from said cracking zone to a second separating zone to separate vapors from a liquid residue and fractionating the last mentioned vapors to separate a distillate having the desired boiling range from condensate oil.

6. A process as defined in claim 5 wherein the condensate oil is combined with the light reflux condensates and the combined stream passed through said cracking zone to effect cracking thereof.

CLAUDE W. WATSON.
